Primary Examiner—Cathy Anne MacCormac

(57) **CLAIM**

I claim the ornamental design for the pet toys on rope, as shown.

DESCRIPTION

FIG. 1 is a perspective view from the front and top of the toy showing my design;

FIG. 2 is a top plan view thereof; the bottom plan view being a mirror image;

FIG. 3 is a rear end view thereof;

FIG. 4 is a front end view thereof; and,

FIG. 5 is a side elevation view; the opposite side elevation view being a mirror image.
